UNITED STATES PATENT OFFICE.

JOACHIM T. HOLTFOTH, OF HIGHLAND PARK, MICHIGAN, ASSIGNEE TO L. A. YOUNG INDUSTRIES, INC., OF DETROIT, MICHIGAN.

SPRING-CUSHION STRUCTURE.

Application filed May 5, 1922. Serial No. 559,738.

To all whom it may concern:

Be it known that I, JOACHIM T. HOLTFOTH, citizen of the United States, residing at Highland Park, county of Wayne, State of Michigan, have invented certain new and useful Improvements in Spring-Cushion Structures, of which the following is a specification.

This invention relates to improvements in spring cushion structures.

The main object of the invention is to provide an improved spring cushion structure well adapted for use as automobile and like cushions in which the frame is very strong and durable and at the same time economical to manufacture and convenient for the attachment of the upholstery thereto.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. 1 is a fragmentary plan view of a cushion structure of the automobile cushion type embodying the features of my invention with the upholstery omitted.

Fig. 2 is an enlarged detail vertical section on a line corresponding to line 2-2 of Fig. 1, the upholstery being shown conventionally.

Fig. 3 is an enlarged detail plan view of the base frame showing the relation of the telescoping end parts thereof.

Fig. 4 is a detail plan view of the base frame showing the telescoping end parts prior to their engagement.

Fig. 5 is an inside elevation of the parts shown in Fig. 4.

Fig. 6 is a transverse section on a line corresponding to line 6-6 of Fig. 3.

Fig. 7 is an end elevation of one of the telescoping parts looking in the direction of the arrows in Fig. 5.

Fig. 8 is an end view looking in the direction of the arrows of Fig. 4.

Fig. 9 is an enlarged detail section corresponding to that of Fig. 2.

Fig. 10 is a detail inside elevation show-

ing a modified form of my invention, the 55 modification being in the omission of the bead at the edge of the bottom channel.

Fig. 11 is a transverse section on a line corresponding to line 11-11 of Fig. 10.

Fig. 12 is a detail plan view of the telescoping parts prior to their engagement.

Fig. 13 is an inside view of the telescoping parts prior to their engagement.

Fig. 14 is an end view on a line corresponding to line 14-14 of Fig. 12.

Fig. 15 is a cross section on a line corresponding to line 15-15 of Fig. 12.

In the drawing similar reference characters refer to similar parts throughout the several views and the sectional views are 70 taken looking in the direction of the little arrows at the ends of the section lines.

Referring to the drawing, the springs 1 are of the helically coiled type. The upholstery is conventionally shown at 2 as is 75 also the top border frame 3 to which the upper ends of the springs are secured. As the details of the top and connections of the springs thereto form no part of this invention they are not further illustrated.

The base frame 4 is of $\mathbb{S}$ cross section providing an upper inwardly facing channel 5 and a lower outwardly facing channel 6, the upwardly facing channel being adapted to receive the bottom coils of the outer or 85 border springs, as is shown in Figs. 1 and 2, the edges of the channel being clamped upon the springs at 7. The lower outwardly facing channel 6 is adapted to receive the lower edge of the upholstery 2 which has a 90 bead 8 therein. The edge of the channel is clamped upon the upholstery after the bead is arranged in the channel, thereby retaining the channel.

The edge of the lower channel is preferably rolled into a bead 9 so that the upholstery is clamped between the medial portion of the base and this bead 9 as shown in Fig. 9. The base is made up, in the structure illustrated, of two sections having telescoping joints, providing a continuous frame with continuous outwardly and inwardly facing channels. One of the channels of each telescoping part is reduced to fit within the corresponding channel of the other 105 part as shown in Fig. 4. The lower telescoping part 9 is reduced to fit within the outer telescoping part 10 and the upper tele-

scoping part 11 is reduced to fit within the outer telescoping part 12. The bead of such telescoping part 9 is cut away to the point 13, so that when the parts are telescoped 5 the ends of the beads abut as shown in Fig. 3.

To lock the parts in engagement the edges of the upper telescoping parts are engaged at 14.

10 In the modified structure shown in Figs. 12-15 inclusive the bead is omitted, otherwise the parts are substantially the same.

With this arrangement, I provide a structure in which the frame is very strong and 15 rigid, the joint being in fact as strong as any other part of the frame, so that the cushion may be very roughly used in shipping and does not give or yield when the upholstery is applied thereto and the continuous 20 open channels are provided and maintained, so that the springs may be positioned as desired without regard to the joints and also the upholstery is supported throughout.

25 My improvements not only result in economy of manufacture but also in securing a very superior structure. Heretofore it has been the practice to provide bridge pieces at the joints and to utilize one of 30 the springs as a bridge piece, and this has always resulted in a weak spot which, by my improvements, has been entirely eliminated.

Having thus described my invention, what 35 I claim as new and desire to secure by Letters Patent, is:—

1. In a spring cushion structure, the combination with the springs and an upholstery covering therefor, of a base frame of S cross section providing an upper inwardly facing spring supporting channel and a lower outwardly facing upholstery securing channel, said lower channel having its outer edge rolled into a bead, said frame comprising 45 telescoping end parts whereby an endless frame with continuous channels is provided, one channel of each telescoping end part being contracted to fit within the corresponding channel of the coacting telescoping end part, the bead of the lower channel being cut away for the length of the telescoping parts to abut with the end of the bead of the outer lower channel, the edges of the 50 upholstery being arranged within the outwardly facing channel which is clamped thereon and certain of the springs being disposed within the inwardly facing channel which is clamped thereon.

2. In a spring cushion structure, the combination with the springs and an upholstery covering therefor, of a base frame of S cross section providing an inwardly facing spring supporting channel and an outwardly facing upholstery securing channel, said 55 frame comprising telescoping end parts

whereby an endless frame with continuous channels is provided, one channel of each telescoping end part being contracted to fit within the corresponding channel of the coacting telescoping end part, the edges of the 70 upholstery being arranged within the outwardly facing channel which is clamped thereon and certain of the springs being disposed within the inwardly facing channel which is clamped thereon.

75

3. In a spring cushion structure, the combination with the springs and an upholstery covering therefor, of a base frame of S cross section providing an inwardly facing spring supporting channel and an outwardly facing upholstery securing channel, said frame comprising telescoping end parts whereby an endless frame with continuous channels is provided, one channel of each telescoping end part being contracted to fit within the 80 corresponding channel of the coacting telescoping end part, the edges of the upper telescoping parts being indented to lock the parts together, the edges of the upholstery being arranged within the outwardly facing 85 channel which is clamped thereon and certain of the springs being disposed within the inwardly facing channel which is clamped thereon.

4. A spring cushion structure comprising 90 a base frame of S cross section providing an upper inwardly facing spring supporting channel and an outwardly facing upholstery securing channel, said lower channel having its outer edge rolled into a bead, said frame 100 comprising telescoping end parts whereby an endless frame with continuous channels is provided, one channel of each telescoping end part being contracted to fit within the corresponding channel of the coacting telescoping end part, the bead of the inner lower channel being cut away for the length of the telescoping parts to abut with the end of the bead of the outer lower channel, the edges of the upper telescoping parts being indent- 105 ed to lock the parts together.

5. A spring cushion structure comprising 110 a base frame of S cross section providing an upper inwardly facing spring supporting channel and a lower outwardly facing upholstery securing channel, said lower channel having its outer edge rolled into a bead, said frame comprising telescoping end parts whereby an endless frame with continuous 115 channels is provided, one channel of each telescoping end part being contracted to fit within the corresponding channel of the coacting telescoping end part, the bead of the inner lower channel being cut away for the length of the telescoping parts to abut with the end of the bead of the outer lower channel.

6. A spring cushion structure comprising 120 a base frame of S cross section providing an inwardly facing spring supporting channel 130

and an outwardly facing upholstery securing channel, said frame comprising telescoping end parts whereby an endless frame with continuous channels is provided, one channel of each telescoping end part being contracted to fit within the corresponding channel of the coacting telescoping end part.

7. A spring cushion structure comprising a base frame of S cross section providing an inwardly facing spring supporting channel and an outwardly facing upholstery securing channel, said frame comprising telescoping end parts whereby an endless frame with continuous channels is provided, one channel of each telescoping end part fitting within the corresponding channel of the coacting telescoping end part.

telescoping end part, the telescoping parts having interlocking indentations therein.

8. A spring cushion structure comprising a base frame of S cross section providing an inwardly facing spring supporting channel and an outwardly facing upholstery securing channel, said frame comprising telescoping end parts whereby an endless frame with continuous channels is provided, one channel of each telescoping end part fitting within the corresponding channel of the coacting telescoping end part.

In witness whereof, I have hereunto set my hand and seal.

JOACHIM T. HOLTFOOTH. [L.S.]
